CLAIM

The ornamental design for a smart switch, as shown and described.

DESCRIPTION

1. Smart switch

FIG. 1.1 is a front, right and top perspective view of the smart switch, showing my design.

FIG. 1.2 is a rear, left and bottom perspective view of the smart switch, showing my design.

FIG. 1.3 is a front elevation view of the design in FIG. 1.1. FIG. 1.4 is a rear elevation view of the design in FIG. 1.1. FIG. 1.5 is a left side elevation view of the design in FIG. 1.1.

FIG. 1.6 is a right side elevation view of the design in FIG. 1.1.

FIG. 1.7 is a top plan view of the design in FIG. 1.1.

FIG. 1.8 is a bottom plan view of the design in FIG. 1.1. The broken line portion of the reproductions is included to show portions of the smart switch that form no part of the claimed design.

1 Claim, 8 Drawing Sheets
